UNITED STATES PATENT OFFICE.

GEORGE A. LAMBERT, OF ANDERSON, INDIANA.

VEHICLE-POLE.

SPECIFICATION forming part of Letters Patent No. 788,654, dated May 2, 1905.

Application filed August 12, 1904. Serial No. 220,490.

To all whom it may concern.:

Be it known that I, GEORGE A. LAMBERT, a citizen of the United States of America, and a resident of Anderson, county of Madison, State 5 of Indiana, have invented certain new and useful Improvements in Vehicle-Poles, of which the following is a full and clear specification, reference being had to the accompanying drawings, in which—

10 Figure 1 is a perspective view of a pole constructed according to the preferred form; Fig. 2, a detail perspective view of the heel portion detached; Fig. 3, a horizontal sectional view through a part of the fold adjacent to the doubletree-bearing; Figs. 4, 5, and 6, cross-sections of the pole, showing various forms of sheet-metal structures.

15 All-wood vehicle-poles are becoming more and more expensive to manufacture each season, as suitable hickory-wood is becoming scarcer and scarcer.

20 It is the object of this invention to permit the utilization of smaller, and consequently cheaper, pieces of the wood to be employed, 25 thus reducing the expense of manufacture to a considerable extent.

25 In my improved pole I make the bent heel-piece *a* of wood in the usual manner; but instead of making it integral with the main or 30 straight part of the pole I make it separately therefrom from a comparatively short piece of wood and attach it to a sheet-metal pole *b*, its forward end being inserted in the rear hollow end of the pole and fastened therein.

35 The metal pole is constructed of folded sheet metal. I prefer constructing the main part of the pole of a single sheet of metal folded on longitudinal converging lines to form a central web portion *c* of two or more thicknesses of metal, as shown in Fig. 4, and oppositely-extending flanges of two or more thicknesses at the upper and lower edges of the web portion. These thicknesses of metal are fastened together in any suitable manner, 40 preferably by rivets passed through the thicknesses composing the web portion. The sides of the channel-iron or I-beam thus formed are bridged over the full length of the fold by shells *f*, semicircular in cross-section, giving

45 the pole the desired shape in cross-section.

The longitudinal edges of these shells are seamed to the longitudinal edges of the flanges *d*, thus forming a very rigid and light pole having a pleasing and substantial appearance. This metal part of the pole can be formed 55 very inexpensively with the proper dies, inasmuch as it is a simple tapering structure without curves.

Instead of constructing the pole in the manner shown in Fig. 4 and above described I 60 may construct it in a variety of ways. Two of these modifications are shown in Figs. 5 and 6. In Fig. 5 the web and flanges are formed of three sheets of metal properly folded and riveted together, the flanges *d'* being 65 of single thicknesses in the web *c'* or three thicknesses. In Fig. 6 the same structure is shown, except that the shells *f* are expanded at the seam, so that their outer surfaces become flush with the outer faces of the flanges 70 *d'* and form a substantially continuous surface, giving to the pole a more regular oval shape in cross-section.

The wood heel has its forward end *g* made straight and slightly reduced in diameter, so 75 as to fit tightly in the hollow pole. Its end portion *g* is slotted vertically for the reception of the central web *c*, and it is fastened in its socket by any suitable means, preferably by the same bolts *h* which fasten the brace-rods to the sides of the pole. If additional fastening devices are necessary, the bolts *i*, which fasten the doubletree bearing-plate *j* to the pole, may also be utilized for this purpose. In some constructions the hammer-strap bolts may also be made to perform the additional function of securing the two parts of the pole together. As shown, the thicknesses composing the central web are slightly 80 spread apart for the passage of the bolt *i*, whereby the bulges thus formed on the exterior of the central web will be forced into the wood of the stem *g*. The doubletree-bolt *k* may also be used in a like manner if found 85 desirable.

90 It will be observed that in the manner set forth in the foregoing a strong and durable pole having as pleasing an appearance as the all-wood poles may be constructed at a greatly-reduced expense in comparison with the all- 100

wood poles, as the comparatively short wood pieces required for the heels can be obtained in large quantities at little expense.

It will be understood that I am not confined in my claims to the exact construction of heel-piece and metal part shown and described, and I therefore reserve the right to vary the construction without departing from my invention. For instance, it might be desirable to construct the straight part of the pole partly of wood instead of entirely of metal, this being within the spirit of the invention, as is obvious, and also that the rear end of the metal part of the pole may terminate short of the king-bolt of the doubletree, so that the lateral bulges shown in Fig. 3 (which would interfere with the insertion of the tongue portion *g*) shall be done away with.

Having thus fully described my invention, what I claim as new, and desire to secure by Letters Patent, is—

1. In a vehicle-pole, the combination of a straight metallic forward portion and a bent wooden heel portion attached to the rear end thereof.

2. In a vehicle-pole, the combination of a bent wood heel portion and a straight metal pole proper hollow at its rear end, the forward end of the heel portion being straight and inclosed in said hollow part.

3. In a vehicle-pole, the combination of a hollow sheet-metal pole part proper and a bent heel portion having its forward end straight and inclosed in the rear end of said pole part proper.

4. In a vehicle-pole, the combination of a straight pole part proper formed of sheet metal folded and made hollow, said hollow part being braced by an internal longitudinal web, a heel portion having its forward end inserted in said hollow pole member, and means for fastening the parts together.

5. In combination with a curved wooden heel portion having a straight forward extension slotted longitudinally, of a metal pole part proper made hollow and provided with a central web, the straight part of the heel

portion being inserted in the rear hollow end of the pole proper and fastened therein.

6. In a vehicle-pole, the combination of a curved heel member and a straight front portion, said front portion being constructed of a central web having top and bottom flanges and shells seamed to the respective top and bottom flanges, whereby the straight portion of the pole is made hollow, the forward end of the heel portion being inserted in the hollow portion and fastened therein.

7. A vehicle-pole having its main forward part constructed of longitudinally-folded sheet metal and its rear or heel portion of wood, substantially as set forth.

8. A vehicle-pole constructed of sheet metal folded on longitudinal lines, the folds being brought together to form a multiple-ply central web and also top and bottom flanges, and separate sheet-metal side walls connecting the flanges on each side.

9. A metallic vehicle pole or shaft consisting of a central longitudinal web provided with lateral flanges, and metal side walls attached at their upper and lower edges to said flanges.

10. A metallic vehicle-pole consisting of a folded sheet-metal central web and separate side walls attached along their upper and lower edges to the respective upper and lower edges of the web.

11. A sheet-metal vehicle pole or shaft consisting of a multiple-ply central web and top and bottom lateral flanges, and single-ply side walls attached to said flanges.

12. A sheet-metal pole consisting of a central web part provided with top and bottom flanges, and side walls or shelves seamed to said flanges along their longitudinal edges.

In testimony whereof I hereunto affix my signature, in the presence of two witnesses, this 9th day of August, 1904.

GEORGE A. LAMBERT.
